UNITED STATES PATENT OFFICE.

CHARLES E. HANSEN, OF PROVIDENCE, RHODE ISLAND, ASSIGNOR TO HANSEN-BENNETT COMPANY, A CORPORATION OF RHODE ISLAND.

DESIGN FOR A SIGNET.

No. 38,936.

Specification for Design.

Patented Dec. 10, 1907.

Application filed October 14, 1907. Serial No. 397,454. Term of patent 3½ years.

To all whom it may concern:

Be it known that I, CHARLES E. HANSEN, a citizen of the United States, residing at Providence, in the county of Providence and State of Rhode Island, have invented a new, original, and ornamental Design for a Signet, of which the following is a specification.

The figure is a plan view of signet embodying my new design.

I claim
The ornamental design for a signet, as shown.

CHARLES E. HANSEN.
